ATHLETE'S HEADGEAR

Michael T. Marietta, Dallas, Tex.

Application November 5, 1954, Serial No. 467,037

5 Claims. (Cl. 2—3)

This application is a continuation-in-part of applicant's prior application 398,322, filed December 15, 1953, for Athlete's Headgear.

This application relates to athlete's headgear and has for an object the provision of a headgear comprising a unitary helmet and mask structure incorporating a reinforcement assuring the integral connection of helmet and mask. The headgear further includes a cover for closing an opening in the rear of the helmet-mask unit.

A further object of the invention is to provide a sturdy athlete's headgear which may be manufactured at low cost and attached to and detached from the wearer's head by the athlete himself with a minimum of effort and inconvenience.

With these objects in view and others which may become apparent as the invention is fully understood, the same resides in the arrangement, combination and construction of elements hereinafter fully and specifically described and the subject matter which applicant regards as his invention or discovery is particularly pointed out and distinctly claimed in the appended claims.

The specification should be read in connection with the accompanying drawing, forming part of the application and wherein:

Fig. 1 is a front perspective of the preferred embodiment of applicant's invention;

Fig. 2 is a rear perspective;

Fig. 3 is a partial vertical section viewed rearwardly.

Fig. 4 is a detail vertical section in or parallel to the plane of symmetry.

In the drawing in which like characters of reference denote like or similar elements, numeral 5 denotes a combined helmet-and-mask including an upper dome-shaped part with ventilating openings 7.

The ears of the wearer are each housed in outwardly bulging portions 9 of generally frusto-conical shape (Fig. 3) including flat platelike members each with a centrally disposed hearing hole 11.

The mask element proper is composed of a chinguard 13 with holes 14. In the chinguard 13 and the cheeks and nose covering apertured part 14 is embedded a reinforcement member 15, preferably of steel, which terminates in loops 17, each embedded in the flat platelike member of an ear-covering portion 9. The front or face part of the reinforcement has an aperture registering with the mouth opening 19 of the mask. A single eye opening 21 separates the upper mask edge from the lower edge of the forehead-covering part of the helmet.

The helmet has at the rear a symmetrically-situated recess 23 open at its lower end. This recess can be closed

2

by a curved cover 25 the inner surface of which is concave. The edge portion of the helmet, bounding the inner and upper end of recess 23, and the upper edge of cover 25 are each provided with a plurality of lacing holes 27, each lined by an eyelet 29. A lacing 31 is threaded through the eyelets and holes and may be secured therein by a knot of the ends and functions as a hinge for the cover.

In order to secure the cover in the recess, a buckle 33 is attached to one end of a strap, the other end of which is fastened to the outer surface of the cover adjacent the lower end of each lateral edge thereof by a rivet 35 (Fig. 3). The outer end portion of a second strap 37 can be laced through and held by the buckle and the other or inner end portion of the strap passes through a slot 39 in the lower end of each marginal helmet portion, bounding the recess, and is fastened on the inner helmet surface by a rivet 35 (Figs. 2, 3).

The mask and helmet and cover may be made of any material, particularly plastic, or leather.

The athlete can with ease put his head beneath the raised cover hinged to the helmet and through the recess into the helmet and thereafter buckle the cover to the helmet.

My invention has had expression in a form which I believe to be the preferred embodiment thereof which has been described in terms employed for purposes of description and not to be construed as limitations, as structural modifications may be resorted to without, however, departing from the spirit of my invention as long as the changes made come within the scope of my invention as defined by the subjoined claims.

What I claim is:

1. In an athlete's headgear the combination comprising a one-piece mask and helmet having at its rear a recess, a cover hingedly connected to the helmet for movement to and from a position closing the recess and operable means fastened in part to the helmet and in part to the cover for securing the cover to the helmet in recess-covering position.

2. The combination according to claim 1 and wherein the securing means comprise a buckle and straps co-operating therewith.

3. The combination according to claim 1 and wherein the hinge comprises holes in the helmet margin surrounding the recess and in the cover margin adjacent thereto and a lacing threaded through the holes.

4. The combination according to claim 3 and wherein the securing means comprise a buckle and straps connecting therewith.

5. In an athlete's headgear the combination comprising a one-piece mask and helmet including outwardly bulging ear-covering portion and a recess in the rear helmet part, a metal reinforcement embedded in the mask part and terminating in loops embedded in the ear-covering portions, and a cover fitting the recess and hinged to the helmet and attachable thereto for closing the recess.
